UNITED STATES PATENT OFFICE.

ABRAHAM WOLF, OF NEW YORK, N. Y.

PICTURE-FRAME.

SPECIFICATION forming part of Letters Patent No. 240,873, dated May 3, 1881.

Application filed July 20, 1880. (No model.)

To all whom it may concern:

Be it known that I, ABRAHAM WOLF, a citizen of the United States, residing in New York city, in the State of New York, have invented 5 certain new and useful Improvements in the Construction of Frames for Pictures, Looking-Glasses, and the like, of which the following is a specification.

I make my frame of sheet metal. The front 10 is in a single piece. By properly operating the dies ordinary sheet metal, as good tinned iron, can be wrought in very perfect forms and made to present a rich, substantial, and massive appearance, with sufficient strength for all ordinary uses. Sheet metal may be readily struck 15 in ordinary dies so as to present a considerable amount of embossed effect; but for rectangular frames a sufficient depth from front to rear, with vertical sides, is best attained by 20 first cutting out a portion from each corner. In forming the frame the cut edges are brought together, and may be afterward secured, either by solder alone or by a suitable internal gusset. The back edge may be for some uses left raw; 25 but I esteem it a much more perfect finish to flange the back edge inward.

The inner edge of the frame involves more elaboration. It is especially important that the frame shall present a neat and finished appearance at the inner edge. It is almost equally important that it shall be plane, so as to make a close joint, with plate-glass applied behind it. A considerable portion of the metal from the interior of the frame, where the picture or 30 looking-glass is to ultimately appear, is removed in as perfect condition as practicable, and may be subsequently used for manufacturing other articles; but a portion around the edge of the interior is left attached to the metal 35 of the frame, and is bent outward. It is extended out from the inner edge of the frame in a plane parallel to the glass, and adapted to lie closely thereto. Beyond this point, in preparing for the reception of the glass, or of the 40 glass and picture, and for securing the same properly in the frame, I can adopt two different plans. One, the simplest, is to use only the metal which comes from the area within the frame, and to bend it sharply backward along 45 a line just exterior to the edge of the glass, and provide holes for the insertion of nails or

other pins, and depend upon such alone as a means for holding the glass and picture and backing-board. A fault with this arrangement is that it is impossible by such metal to cover 55 the corners of the picture. A large portion along each of the edges can be thus bent, and makes a secure support, and with the addition of nails or pins a secure holding means is furnished to retain the glass, picture, and back 60 board; but the corners, being exposed, are liable to gather dust or to become otherwise demoralized, and the effect is liable to extend inward, so as to damage the visible part of the picture or of the glass. A better plan is to 65 provide a separately-formed piece of sufficiently stout sheet metal, and fit it to the turned-out flange of the main body, soldering it in such position that it serves, in effect, as a unit therewith; while, by reason of its being made from 70 a separate piece of suitable size, it may protect all parts of the edge of the glass and of the picture and backing-board, the corners included.

The following is a description of what I consider the best means of carrying out the invention. 75

The accompanying drawings form a part of this specification.

Figure 1 is a face view of the frame complete. 80 Fig. 2 is a back view. Fig. 3 shows the metal after it is cut in the proper condition, but before it has been formed into the required shape by dies or otherwise. Fig. 4 is a face view of the corner of the frame on a larger scale. Fig. 85 5 is a cross-section through the completed frame, and also through the additional parts which it is intended to contain. Fig. 6 is a cross-section through a modification. Fig. 7 is a cross-section corresponding to Fig. 5, but 90 with the glass and backing-board secured without nails. Fig. 8 is a cross-section through a modification.

Similar letters of reference indicate corresponding parts in all the figures. 95

Referring to Figs. 1 and 2, A is a plane surface of sheet metal, which is left unaffected by the treatment, and forms a plane face to the finished frame. A' is a series of beads exterior to A. A² is a part bent at right angles 100 to A, and A³ a portion near the edge, which is bent inward at right angles to A². A⁴ is a

series of beads interior to A. A⁵ is a portion extending backward from A⁴ at right angles to A; A⁶, a portion extending outward in a plane parallel to A, and A⁷ a portion bent directly backward from and at right angles to A⁶. The portion A⁷ is punched or otherwise perforated to receive nails B, which are driven into or over an ordinary wood back, C. In front of the back C, and between it and the flat surfaces of sheet metal A⁶, lies the glass D. Between the glass D and the back C a picture may lie in the ordinary manner. The depth of the part A⁵ should be slight, to conform to the present ordinary taste in regard to frames; but that and all the other parts may be varied within wide limits. It is important that the surface A⁶ be so held as to fit closely against the plane face of the glass D, especially at the inner edge.

In the modification shown in Fig. 6 the metal is not extended rearward from the outer edge of A⁶. The metal is sheared by dies or otherwise, so as to bring the edge in the plane portion A⁶. A piece of sheet metal, separately formed by hand or by machinery, as shown by M M', is applied in the position shown, and secured by soldering or otherwise. This modification may be made more complete than that shown in Figs. 1 and 2, because if due care is exercised in the forming and soldering, to avoid distortion of the metal at any stage, the surface A⁶ makes the same plane bearing for the front of the glass as before, while the piece M M' may not only afford a holding material for the nails or other fastenings, B, along the middle portion of each edge of the glass picture and back, but may, by reason of its being separately made, be extended quite up to the corners, and protect the corners equally with other portions.

The part M M' may be formed without joint from a sufficiently large rectangular piece of metal, the center, which is removed, being capable of subsequent use for other purposes; or I can make the part M M' from a long narrow strip of metal, forming it around by any suitable tools, and joining the ends by solder or otherwise. I slit the back edge of the part A⁷, and bend any desired portion of the slit metal inward to lap upon the wood C, and thereby confine it without the necessity of

nails. This can be equally well done with the added piece M. Fig. 7 shows such mode of fastening at A⁸.

Modifications may be made in the proportions within wide limits without sacrificing the advantages of the invention. It produces a frame which is jointless, and complete in its entire front face, may be made highly decorative, and is absolutely proof against warping and all ordinary destructive agencies. My frames may be more than usually strong. They may be produced at very slight cost by suitable machinery.

It is obviously not important that the front and main surface, A, of the frame shall be plane. It may be varied according to taste.

I have in my experiments observed a disposition of the metal to crinkle at the corners. A good way to avoid this may be to produce by the dies an ornament which will take up the surplus metal.

Fig. 8 is a section through a further modification. In this the part A⁶ is omitted, and the part M' is formed forward at the inner edge, as indicated by M². The solder joins the part M² to the part A⁵.

I can make the part M M' M² from separate strips of metal, joined together or not, but bent and soldered to the portion A⁶, as shown in Fig. 8.

I claim as my invention—

1. The rectangular picture-frame, of sheet metal, herein described, having the front A in one piece without joint, the outer surface A', and the inner edge, A⁴ A³ A⁶, formed under and bent outward in a plane to match the plane surface of the glass, arranged in the ordinary position, as herein specified.

2. In a picture-frame, the backwardly-extended portion A⁷, in combination with the plane portion A⁶, produced in one piece with the main body A⁵ A⁴ A³ A² A' A, as herein specified.

In testimony whereof I have hereunto set my hand, at New York city, New York, this 19th day of July, 1880, in the presence of two subscribing witnesses.

ABRAHAM WOLF.

Correction in Letters Patent No. 240,873.

It is hereby certified that in Letters Patent No. 240,873, issued May 3, 1881, to Abraham Wolf for an improvement in "Picture Frames," on page 2 of the printed specification attached to and forming a part of said Letters Patent, in line 86, the reference letter between "A⁴" and "A⁶" was erroneously printed "A³" instead of "A⁵;" that the proper corrections have been made in the files and records pertaining to the case in the Patent Office, and are hereby made in said Letters Patent.

Signed, countersigned, and sealed this 21st day of June, A. D. 1881.

[SEAL.]

A. BELL,

Acting Secretary of the Interior.
